UNITED STATES PATENT OFFICE.

WILLIAM EVERSON, OF ALMA, NEBRASKA.

AEROCYCLE.

1,374,143.

Specification of Letters Patent.

Patented Apr. 5, 1921.

Application filed June 21, 1920. Serial No. 390,527.

To all whom it may concern:

Be it known that I, WILLIAM EVERSON, a citizen of the United States, residing at Alma, in the county of Harlan and State of 5 Nebraska, have invented certain new and useful Improvements in Aerocycles; and I do declare the following to be a full, clear, and exact description of the invention, such as will enable others skilled in the art to 10 which it appertains to make and use the same.

This invention relates to an improved aerocycle for use in connection with an aeroplane and one object of the invention is to 15 provide an aerocycle so constructed that it may be very easily associated with a monoplane or biplane of a conventional construction, thus permitting it to be used in connection with aeroplanes of a construction al- 20 ready in use and making it unnecessary to provide a special construction of plane in order to permit this aerocycle to be used in connection with the same.

Another object of the invention is to so 25 construct this aerocycle that it may be built upon the principle of a gyroscope and used for lifting the aeroplane vertically, for moving the plane ahead or for retarding the plane and permitting the plane to hover in 30 the air or settle and thus make a squash or vertical landing. It will thus be seen that with this improved device, the plane may move vertically from the ground to a desired height and then be propelled for- 35 wardly and after the flight is finished, the plane may be brought to a stop while in the air and then caused to descend in a vertical plane and alight upon the ground, the roof of a building or deck of a ship.

40 Another object of the invention is to so construct the device that the plane may be driven at varying speeds.

This invention is illustrated in the accom- 45 panying drawings, wherein:

Figure 1 is a fragmentary view of an aeroplane of the biplane type having the im- 50 proved aerocycle associated therewith, the view being partially in side elevation and partially in vertical section, along the line 1—1 of Fig. 3,

Fig. 2 is a sectional view taken along the line 2—2 of Fig. 1, and

Fig. 3 is a sectional view taken along the line 3—3 of Fig. 2.

55 This aerocycle is intended for use in connection with an aeroplane of a conventional

construction and has been shown applied to a biplane of the "Curtiss" type. It is to be understood, however, that the device can be applied to a monoplane if so desired. 60 This aeroplane is provided with the usual body or fuselage 1 having the forward and rear cockpits 2 and 3 and having the motor 4 mounted in the forward or nose portion and the aeroplane will be provided with the 65 usual upper and lower wings 5 and 6 and landing gear 7. This device is provided with a frame having upper and lower longitudinally extending bars 8 and 9, cross bars 10 and vertical bars 11, the bars being 70 connected by couplings 12 to provide a strong and rigid frame. This frame will be formed of aluminum or of any other suitable material which will be light in weight but at the same time strong and durable. The 75 frame extends upon opposite sides of the fuselage as shown in Fig. 2 and will carry the gyroscopes having the propellers associated therewith, the gyroscopes being positioned upon opposite sides of the fuselage 80 as shown and rotating in opposite directions thus equalizing the power developed so that the same power will be exerted upon both sides of the fuselage and the aeroplane thus lifted without creating force which might 85 tend to twist the plane and strain the portions thereof.

Each of these gyroscopic propellers is provided with a ring 13 which is positioned vertically in the gap between the wings and 90 within the aerocycle frame and will be rotatably held in place by shoes 14, the shoes being carried by the intermediate vertical bars 15 and cross bars 16 which will be wider and flatter than the remaining bars 95 used in constructing the aerocycle frame. These shoes have concaved faces for engag- 100 ing the rings 13 as shown in Fig. 1 and will be provided with side flanges 14 for engag- 105 ing the side edge faces of the rings and prevent the rings from having transverse movement. A shaft 17 is positioned as shown in Fig. 2 and provided with a hand wheel 18 by means of which it may be ro- 110 tated and this shaft extends longitudinally of the aerocycle frame upon opposite sides of the fuselage and carries gears 19 which engage the teeth 20 of the rings 13 and will cause the rings to be rotated an equal amount when the shaft 17 is rotated.

In order to lift and propel the aeroplane, there has been provided in each of the rings

13, a shaft 21 which is journaled in bearings 22 carried at oppositely disposed points upon the rings and this shaft 21 carries a propeller 23 having a hub 24 from which 5 extend the blades 25, the outer end portions of which are connected with the bracing bands 26. The blades of the propeller at one side of the fuselage will be inclined in an opposite direction to the propeller 10 upon the opposite side of the fuselage, and therefore, when the shafts 21 are rotated in opposite directions, the propellers will both be rotated to lift the machine from the ground. They will, however, counter- 15 balance each other and prevent the plane from having a tendency to turn in a circle.

In order to rotate the two shafts 21, a gear 27 has been mounted upon the engine shaft and meshes with a gear 28 carried 20 by a driving shaft 29. This driving shaft 29 extends longitudinally of the aerocycle frame and carries gears 30 which mesh with the gears 31 mounted upon the shafts 21. A shaft housing or casing 32 is provided 25 about the shaft 29 and motor shaft and gear 27 and is provided with end sections 33 which are rotatably connected with the intermediate portion of the casing by oil tight bearings 34 and have their outer ends provided with gear housings 35. The gear 30 housings 35 are positioned about the shafts 21 and gears 30 and 31 and have their outer 30 end portions rotatably connected with oil tight bearing plates 36 which form closures for the outer ends of these housings 35. These heads 36 are engaged by the supporting and bracing bars 37 and 38 and will be 35 securely held in the position shown. It will thus be seen that the outer sections 33 of the shaft housing 32 will be rotatably mounted between the bearings 34 and 36 thus permitting these outer sections to rotate with the rings 13 when these rings are rotated by turning of the shaft 17.

When the aeroplane is in use, the motor will be started in the usual manner and the pilot and observer or passenger will occupy the forward and rear cockpits. The motor will be provided with suitable treads 39 and 40, one being for use in controlling a 50 suitable clutch for transmitting rotary movement to the shaft 29 and the second being used for controlling the speed. The clutch will be moved to transmit rotary movement to the shaft 29 with the shaft rotating at slow speed, and the propellers of the gyroscope will be rotated. If the shafts 31 are positioned in a vertical position as shown in Fig. 1, the draft or propeller wash will pass downwardly and will 55 pass through the openings 41 formed in the lower plane. When the speed of rotation is increased to the necessary amount, the aeroplane will be lifted off of the ground and after it has arisen to the desired height,

the shaft 17 can be rotated by means of the hand wheel 18 and the rings 13 of the gyroscopes rotated to extend the shafts 21 in a horizontal position. The aeroplane will then be propelled forwardly and if it is 70 desired to climb rapidly, the rings can be rotated to extend the shafts 21 forwardly and upwardly. When it is desired to retard movement of the plane and make a landing, the rings of the gyroscopes will be 75 rotated to extend the shafts 21 rearwardly and upwardly and the propellers will then form a check which will halt the forward movement of the plane. The propellers can then be returned to the vertical position and 80 rotated at a reduced speed, so that the plane will remain stationary or gradually settle and light upon the ground. It will thus be seen that with this device a flight may be started from a small space and a landing 85 made upon a small space.

What is claimed is:

1. The combination with an aeroplane having a fuselage and wings, of an elevating and propelling attachment comprising a frame extending upon opposite sides of the fuselage, rings positioned vertically in the frame and rotatably mounted, shafts rotatably mounted in the rings, propellers carried by the shafts, a driving shaft extending longitudinally of the frame and adapted to receive rotary movement from the motor carried by the fuselage, means for transmitting rotary movement from the driving shaft to the shafts rotatably mounted in the rings, and means for rotating the rings to an adjusted position to adjust the angular position of the propeller carrying shafts.

2. A propelling and elevating attachment for an aeroplane comprising a frame for extending transversely of a fuselage upon opposite sides thereof, gyroscopic propelling means carried by the frame in the end portions thereof, each comprising a ring rotatably mounted vertically in the frame, a propeller shaft journaled in the ring, a propeller mounted upon the shaft, a rotatably mounted driving shaft for transmitting rotary movement to the propeller carrying shafts of the rings, and means for rotating the rings and retaining the same in an adjusted position with the propeller carrying shafts extending at a desired angle.

3. The structure of claim 2 having the blades of one propeller extending at an angle opposite to the angle of the blades carried by the second propeller, the means for transmitting rotary movement from the driving shaft to the propeller shafts causing one shaft to rotate in an opposite direction to the rotation of the second propeller shaft.

4. The structure of claim 2 having a shaft casing for the driving shaft provided with

- an inner section positioned about the intermediate portion of the driving shaft and terminating in coupling heads, and outer-sections for the shaft casing having their inner 5 ends rotatably connected with the coupling heads of the intermediate sections and having their outer end portions provided with housings engaging the propeller shafts, and heads for closing the housing at the outer 10 ends of the shaft casing forming bearings for the outer ends of the outer casing sections and permitting the outer casing sections to rotate when the rings are rotated in the frame.
- 15 5. A propelling means for an aeroplane having a fuselage and wings, said propelling means comprising a frame for extending transversely of and beyond opposite sides of the fuselage, said frame having longitudinally extending bars and standards and cross bars connecting the longitudinally extending bars, rings positioned vertically in the frame, shoes carried by certain of the cross bars and vertically extending bars and engaging the 20 rings to rotatably mount the rings and hold the rings against transverse movement, a rotatable shaft extending longitudinally of the frame and having gears engaging gear teeth of the rings for imparting rotary movement to the rings, propeller shafts journaled in the rings, a driving shaft rotatably mounted and extending longitudinally of the frame and having gears engaging gears carried by the propeller shaft, and propellers carried 25 by the shafts for imparting vertical movement to an aeroplane when the propeller shafts are vertical and for imparting forward movement to the aeroplane when the propeller shafts are horizontal.
- 30 6. The combination with an aeroplane including a fuselage and wings, of a frame extending transversely of the fuselage and longitudinally of the wings, gyroscopic propelling means in the frame upon opposite sides of the fuselage including rings positioned vertically and rotatably mounted, propeller shafts journaled in the rings, means for rotating the rings to adjust the 35 position of the shafts, propeller blades carried by the shafts, and means for imparting 50 rotary movement to the propeller shafts with one propeller shaft rotating in an opposite direction to the second.
7. A gyroscopic propelling attachment for an aeroplane comprising a frame for extending longitudinally of the wings and transversely of the fuselage of an aeroplane, rings rotatably mounted in the end portions of the frame and positioned vertically therein, means for imparting rotary movement to the 55 rings and releasably holding the same in a set position, propeller shafts journaled in the rings, a driving shaft having geared connection with the propeller shafts for transmitting rotary movement to the same in opposite directions, a shaft casing for the driving shaft having its intermediate section and outer sections rotatably connected with the inner section and having connection with the propeller shafts, and propellers carried 60 by the propeller shafts within the rings.
8. The combination with an aeroplane having a fuselage and upper and lower wings, the lower wings being provided with openings upon opposite sides of the fuselage, a frame positioned between the upper and lower wings and extending upon opposite sides of the fuselage, and gyroscopic propelling means in the frame having rings positioned vertically in the frame and rotatably 65 mounted above the openings in the lower wings of the aeroplane, propeller shafts journaled in the rings, propellers carried by the shafts, means for transmitting rotary movement to the propeller shafts from a 70 source of power and means for rotating the rings and releasably holding the same in a set position.
- In testimony whereof I have hereunto set my hand in the presence of two subscribing 75 witnesses.
